UNITED STATES PATENT OFFICE.

AUGUST JOHNSON, OF MANKATO, MINNESOTA.

DESIGN FOR A SMOKER'S STAND.

61,393.

Specification for Design.

Patented Aug. 22, 1922.

Application filed February 6, 1922. Serial No. 556. Term of patent 14 years.

To all whom it may concern:

Be it known that I, AUGUST JOHNSON, a citizen of the United States, residing at Mankato, in the county of Blue Earth and State of Minnesota, have invented a new, original, and ornamental Design for Smokers' Stands, of which the following is a specification, reference being had to the accompanying drawing, forming part thereof.

The figure is a perspective view of a smoker's stand, showing my new design.

I claim:

The ornamental design for a smoker's stand, as shown.

AUGUST JOHNSON.
